United States Patent Office.

JOHN DANNER AND SAMUEL DANNER, OF CANTON, OHIO.

Letters Patent No. 63,998, dated April 23, 1867.

IMPROVED BED BOTTOM.

The Schedule referred to in these Letters Patent and making part of the same.

TO ALL WHOM IT MAY CONCERN:

Be it known that we, JOHN DANNER and SAMUEL DANNER, of Canton, in the county of Stark, and State of Ohio, have invented certain new and useful improvements in Bed Bottoms; and we do hereby declare the following to be a full, clear, and exact description of the same, reference being had to the accompanying drawings, making a part of this specification, in which—

Figure 1 represents a top plan of one of the bed bottoms with one of the slats removed to show its support underneath.

Figure 2 represents an end elevation of one of the slat supports, and of the slat retainers thereon.

Figure 3 represents a longitudinal vertical section through a bed frame and bottom; and

Figure 4 represents a perspective of the under side of one of the slats, and showing the shape and construction of that portion of the slat support that is on said slat.

Similar letters of reference, where they occur in the several separate figures, denote like parts of the bed and bottom in all the drawings.

Our invention consists in uniting and supporting the slats upon and to the cross-pieces resting on or in the bedstead or bed frame, by means of certain castings which, whilst they admit of free play endwise to the slats, still confine them to the slat supporters or transverse pieces of the bedstead or frame.

To enable others skilled in the art to make and use our invention, we will proceed to describe the same with reference to the drawings.

A represents a bedstead, lounge frame, or other similar article, in which is supported, in any of the usual well-known ways, the transverse bearing pieces B, one at or near each end thereof. On these bearing pieces B we arrange a series of U-shaped brackets, a, made of cast metal, the particular form of which brackets is better seen in fig. 2. They are held to the bearing pieces by a screw or screws, or otherwise, and have holes made through their arms for an object to be hereafter mentioned. C represents the slats composing the bed bottom. They run longitudinally of the bedstead or frame, and have upon their under sides, and at or near each of their ends, castings, b, that have edged bearings, c, on them, and a flange, d, as shown at fig. 4. And to make them light, their centre portions, e, are cast open. These castings b may be secured to the slats by screws or otherwise. The castings a having been properly arranged and fastened to the bearers B, and the castings b having been properly placed and fastened to the slats C, the latter are placed in or on the harp or lyre-shaped pieces a, metal to metal, and then, to keep them from being raised out, a string or cord, f, may be passed through the holes in the arms of the brackets a, which will retain them in place should the bedstead or frame be moved. As a general thing, the slats will lie in their places, and can yield to any superincumbent weight, but restrained from going too far by the flanges d on their castings.

Having thus fully described our invention, what we claim therein as new, and desire to secure by Letters Patent, is—

In combination with the slats of a bed or lounge bottom, and the bearers that support it, the castings a, b, made and operating substantially in the manner and for the purpose described.

JOHN DANNER,
SAMUEL DANNER.
